UNITED STATES PATENT OFFICE.

SIMON B. STORER, OF SYRACUSE, NEW YORK.

MAIL-DISTRIBUTING SYSTEM.

1,261,968.

Specification of Letters Patent. Patented Apr. 9, 1918.

Application filed December 11, 1914. Serial No. 576,667.

To all whom it may concern:

Be it known that I, SIMON B. STORER, a citizen of the United States, and resident of Syracuse, in the county of Onondaga, 5 in the State of New York, have invented new and useful Improvements in Mail-Distributing Systems, of which the following, taken in connection with the accompanying drawings, is a full, clear, and exact description.

This invention relates to certain improvements in mail distributing systems in post offices and other distributing stations where such mail matter is assorted and deposited 15 in separate compartments for subsequent delivery over different routes by special carriers.

Under the present system in the larger distributing stations, such as city post offices, 20 the mail matter designated for different routes of delivery is assorted and placed by hand into separate compartments of the distributing case corresponding to such different routes for subsequent delivery by the 25 carrier assigned to such routes, each route, carrier and compartment being usually designated by a special number to facilitate the work of assorting and delivering, but so far as I am aware no provision is made for ascertaining with any degree of accuracy the 30 number of pieces of mail matter distributed, or relative speed, efficiency of the several distributors.

The main object is to associate with each 35 distributing case simple and efficient means for automatically registering the number of pieces of mail matter assorted and distributed by the clerk assigned to that particular case, so that the total number of such 40 pieces handled by the distributing station for any predetermined interval of time may be ascertained by adding the totals of registers for the several distributing cases.

Another object is to enable the inspector 45 to determine at a glance the relative speed efficiency of the several assorting clerks so that the relative merits of such clerks may be properly established.

Other objects and uses will be brought 50 out in the following description.

In the drawings—

Figure 1 is a diagrammatic view of an

electrical mail distributing system showing various features of my invention as used in connection with a single compartment of 55 the distributing case, not shown.

Fig. 2 is a front face view of a distributing case, in this instance having a series of compartments, and a corresponding number of mail feeding devices, together with 60 the driving motor for said devices and the counter mechanism and circuit breaks for controlling the operation of the counter mechanism.

Fig. 3 is a transverse vertical sectional view of a portion of the distributing case and mail feeding mechanisms associated therewith, taken on line 3—3, Fig. 2.

Fig. 4 is an enlarged horizontal sectional view through a portion of the mail feeding 70 devices in the plane of the meeting faces of the feeding rollers, showing more particularly the relative positions of the mail guides and mail operating triggers for actuating the circuit interrupter of the counter operating circuit.

Fig. 5 is an enlarged detail sectional view through one end of the supporting shafts for the feeding rollers.

Fig. 6 is an enlarged rear elevation of 80 the counter support, showing a portion of the counter and its operating mechanism, including an electro-magnet instead of the solenoid shown in Fig. 1.

Fig. 7 is an enlarged vertical section of 85 a portion of the supporting frame for the feeding rollers, showing one of the circuit closers or interrupters of the counter circuit.

The apparatus forming the subject-matter of my invention is adapted to be used in 90 connection with a distributing case —A— having one or more compartments (in this instance 8) arranged in tiers and numbered respectively from one to eight inclusive.

Associated with the distributing case is 95 an upright frame —1— carrying a plurality of mail feeding devices —2— corresponding in number to the number of compartments —a— and registering with their respective compartments to feed the assorted mail thereinto.

Each feeding device consists in this instance of a pair of feeding rollers —3— and —4— mounted respectively upon hori-

zontal shafts —5— and —6—, the lower shaft —5— being driven by any suitable moving power, such as an electric motor —7—, through the medium of belts —8— and pulleys —9—.

The ends of the upper shaft are journaled in suitable bearings —10— which are movable vertically in openings —11— in the upright sides of the frame —1— and are 10 spring-pressed downwardly by coil springs —12—, so as to yieldingly hold the upper rollers —4— in running contact with the underlying rollers —3—, thereby permitting mail matter of different thicknesses to 15 be passed through the feeding devices, the upper roller —4— being driven by friction with the mail matter while the latter is being fed forwardly by the lower rollers —3—.

The shafts —5— and —6— extend across 20 the front end of all of the compartments in the particular tier with which they are associated and carry a series of the feeding devices —2—, one for each compartment.

These shaft devices are preferably driven 25 at a sufficiently high rate of speed to prevent the possibility of the pieces of mail matter following each other end to end; in other words, more rapidly than it would be possible for the operator to feed them to the 30 rollers by hand, this speed of movement also serving to impel the mail matter forwardly with sufficient momentum to deliver them into the respective pockets.

The several feeding devices for each tier 35 of compartments are preferably located in a horizontal plane some distance above the bottom of said compartments to allow a considerable number of mail matter to be deposited into such compartments without interfering with the feeding operation, and for this purpose, I have associated with each feeding device a mail guide —13— leading from said feeding device to the corresponding compartments of the distributing case 40 —A—, with their upper faces in a plane substantially coincident with that of the meeting faces of the feeding rollers, said guides being preferably carried by lengthwise bars —14— on the frame —1—.

50 Registering mechanism.

The means for registering the number of pieces of mail matter delivered into the distributing case by any one or more of the 55 feeding devices comprises a counter —15— of any well known commercial type having a rock shaft —16— to which is secured a crank-arm —17—, the latter being operated repeatedly by successive pieces of mail matter passing through any one of the feeding devices into the distributing case by means of a suitable electric device, such as a solenoid —18—, shown in Fig. 1, or an electro-magnet —18'— shown in Fig. 6.

The solenoid or magnet, as the case may be, is connected in a battery circuit —19— having one or more (in this instance 2) normally open electric switches or interrupters —20—, one for each set of feeding devices for each tier of compartments, so that the 70 closing of any switch will energize such electro-magnet or solenoid to cause the operation of the counter.

The closing of the switch or interrupter is controlled entirely by the individual 75 pieces passing along either guide —13— to the corresponding compartment of the case —A—, and in order that this closing of the counter circuit may be positive and reliable for each piece of mail matter, I have provided a series of triggers —21—, one for 80 each compartment, said triggers being mounted in sets, one set for each tier of compartments upon a rock shaft —22— which is also journaled in the upright sides of the 85 supporting frame —1— in a plane just above that of the meeting edges of the feeding rollers —3— and —4— of the corresponding set, so as to allow the mail matter to pass between the shaft and guide in transit to the 90 distributing case.

Each trigger normally projects through an elongated slot or opening —23— in its corresponding guide —13— and is provided with a forwardly projecting shoulder —24— 95 normally resting upon the portion of the guide just in advance of the slot —23— to limit its downward movement and to keep the lower edge of the trigger at an acute angle with the upper face of the guide. 100

Associated with each trigger or set of triggers is an upwardly projecting arm —25— rigid therewith or with the shaft —22— with its upper end normally in close relation to one of the terminals of the switch 105 —20—, such terminal being preferably yielding to contact with the other terminal, and thereby close the circuit through the electric device for operating the counter.

It is now clear that as each individual 110 piece of mail matter is fed by hand to the feeding rollers —3— and —4—, the latter will instantly carry the mail matter forwardly causing its forward end to ride along the upper face of the guide —13— 115 and against the lower edge of the trigger —21—, thereby lifting said trigger a sufficient distance to allow the letter to pass along the guide and into the corresponding compartment of the distributing case, and 120 at the same time causing the arm —25— to close the switch —20— for energizing the electrical device —18— to operate the counter —15—, the return of the spring terminal which is engaged by its operating member serving to assist the weight of the trigger —21— to return the latter to its normal 125 position, this operation being repeated as

each piece of mail matter is fed to the distributing case by any of the feeding devices.

The main object in using the feeding rollers —3— and —4— is to expedite the work of distributing the mail to the several compartments, but it is evident that the counting mechanism would be similarly operated by forcing each individual piece of mail matter along the guide —23— and into the corresponding compartment of the case —1—, and therefore, I do not limit myself to the use of mechanical feeding devices.

It is also evident that if the counter is to be located on the frame —1—, it may be operated by any suitable mechanism capable of transmitting motion from either rock shaft —22— to the crank-arm —17.

In most instances, however, this counter will be located at a remote distance from its distributing case out of the way of the operator and in such position that it could not be tampered with by unscrupulous employees.

In other cases, it might be desirable to place the several counters, one for each distributing case, in the office of the post master or inspector, and I have, therefore, shown a second counter —15— as operated by a separate solenoid —18— which is connected in series with the solenoid —18— so that the individual pieces of mail matter passing through the apparatus into the distributing case and operating the counter —15— will also operate the counter —15'—, thus permitting the post master or inspector to see at a glance the total amount of mail assorted and distributed by any one of the assorting clerks at any time.

As a further check upon the faithfulness and relative speed of operation of the various distributing clerks, I have provided what may be termed a graphic recorder —26— of any well known construction, having relatively movable impression-receiving and impression-making devices, one of which as a roll of paper —27— is chronometer rotated at a relatively slow speed, while the other, or marker —28— is electrically operated by any well known form of magnet, axially across the moving sheet —27—.

The electrical device for operating the marker 28 is connected in a branch circuit —29— having plug terminals —30— adapted to be plugged into a normally closed switch —21— consisting of two terminals which are normally spring-pressed together to maintain a closed circuit through the solenoid —18— and —18'—, and at the same time permitting the branch circuit —29— to be coupled in series in the solenoid circuit whenever it is desired to ascertain the amount or rate of work of any one or all of the distributing clerks, it being understood that one of these graphic recorders

—28— may be provided for each distributing case and that all of them will be located at some central point remote from the distributing room, as for example, in the post master's or inspector's office.

It is evident that this graphic recorder —26— may be used independently of the counter mechanism, if necessary or desirable, and that it might be permanently connected in the circuit —19— under which conditions, the marker —28— would be shifted vertically one tooth space with each tripping movement of the trigger —21— by the individual pieces of mail matter passing along the guide —18— and into the distributing case.

The operating mechanism for the marker is adjusted so as to move the marker —28— a short distance only along the sheet —27—, at each operation, and it is, therefore, evident that if the mail matter is fed into the machine or distributing case continuously or in quick succession, the line marked upon the sheet —27— will extend in a more or less irregular spiral or stepped diagonal line around the sheet.

On the other hand, if there is no mail matter passing through the device it will be indicated on the sheet of the recorder by a straight circumferential line, and it, therefore, follows that if a certain amount of mail matter is passed through the device rapidly and then the operator rests or refrains from work for any considerable period of time, it will be indicated on the sheet of the recorder by a diagonal line terminating in a straight line which shows at a glance that the operator has failed to assort mail for the period of time indicated by such straight line, and may be asked for an explanation of such condition.

It is also apparent that two operators working faithfully side by side on two different distributing cases may vary materially in the amount of work accomplished for the same period of time, which also will be shown upon their respective recorders, in that the line made by the recorder for the employee feeding the greatest amount of mail matter will appear more generally diagonal than that indicated by the recorder of the other workman, thus permitting the officials of the post office or other distributing station to determine the relative merits of both workmen for any period or periods of time.

The graphic recorder shown in Fig. 1 is in many respects similar to that commonly used in electrical appliances, as a graphic meter, in which when the marker is raised to a predetermined position automatically drops to its starting position so that the device is capable of making any number of records for predetermined intervals of time.

What I claim is:

The combination with a mail-assorter's case having a plurality of separate compartments for receiving the assorted mail, of continuously-operating mechanical devices for feeding the assorted mail into corresponding compartments, and means controlled by the pieces of mail, while actuated by their feeding devices, for recording the

rate of delivery of said mail to the compartments collectively.

In witness whereof I have hereunto set my hand this 8th day of November, 1914.

SIMON B. STORER.
